SURFACE COVERING FOR BUILDINGS AND
THE LIKE

Bert G. Goslin, Battle Creek, Mich.

Application August 16, 1937, Serial No. 159,301

17 Claims. (Cl. 108—8)

The present invention relates to surface coverings, and more particularly to surface covering elements adapted to be laid so as to produce a stone wall appearance.

In the past frame buildings, and the like, have commonly had their side surfaces covered with either siding or wooden shingles. In order to preserve and retain the appearance of such elements, it is necessary to paint or stain same at frequent intervals and between applications of paint, to wash the particular surface. To overcome the necessity of painting or staining of building side walls, it has long been common practice to construct such surfaces of brick or stone. The initial cost of such construction, however, is exceptionally high and construction progress slow. To overcome some of these shortcomings, it has recently been proposed to cover the side walls of buildings with asbestos shingles, since such covering is relatively permanent and does not require paint. These shingles, like any other exposed surface, become dirty in a short time, and in case of the conventional white or light gray shingles, it becomes necessary to wash the exposed surface of same at intervals of a year or two in order to retain the desired appearance. The necessity of washing, however, overcomes part of the advantages of using asbestos shingles for this purpose. Stone wall buildings, on the other hand, are of ancient origin and are expected to weather and become dirty. In fact, some architects specify weathered-stone for use in the construction of new houses and other buildings in order to obtain the desired appearance. With this in mind, the present invention has been directed to a surface covering which will simulate a stone wall laid with rectangular stones in courses, and hence eliminate the necessity of painting and washing the wall in its final laid form.

Accordingly, among the objects of the present invention, is the provision of elements adapted for laying in courses having alternating wide and narrow exposure, and with which may be used at intervals, substantially rectangular two-course height elements.

Another object of the invention is the provision of elements of wide and narrow exposure which may be cut from a blank with either no waste or substantially none.

Another object is to provide a combination of elements that is very economical to use due to the moderate total surface area of same required to cover a "square" of wall surface.

Another object is to provide elements wherein

the narrow exposure elements have long tongues on their upper edges, and the wide exposure elements have short tongues on their upper edges. This provides a combination which may be laid in alternating wide and narrow exposure courses and wherein the joints at the ends of each element, when laid over the center of a tongue on the next lower element, will thus provide fully under-covered joints with the tongue extending above the bottom of the next higher course, which obviates the necessity of using mortar joints or strips under each joint to avoid leakage.

Another object is to provide elements which may be laid up in manner such that there are no joints wherein leakage may take place direct to the surface behind such joint.

Another object is to provide elements wherein there are no exposed nails to pull under exposure to the sun, wear out, rust, or cause discoloration streaks.

A further object is to provide the two-course substantially rectangular elements with ears on the sides of same at the upper corners thereof, thus producing a side coverage joint, said ears being provided with means for anchoring same to the surface being covered.

A further object is to provide elements which do not have to be laid perfectly in line and with straight tight joints, since no one expects the edges of hewed stone to be exactly in a straight line, and the same applies to an article simulating such appearance. This of itself results in a saving of labor, since it eliminates the necessity of hand rasping of joints to make a tight fit, a thing which is standard practice today with asbestos shingles used for siding.

A further object is to provide such elements in preferred construction with notched side edges to give the appearance of mortar filled vertical joints, and at the same time prevent vertical "wind tunnels" at the joint.

A still further object is to provide the wide and narrow exposure elements with nail holes at a point under the overlap of the next higher course and at a point wherein at least part of the holes will be adjacent the upper end of the tongues of the next lower course, so that by passing a nail through each of such holes and dropping the element down until the nails contact the top of the tongue or tongues of the next lower element or elements, the proper exposure spacing will be obtained.

A still further object is to provide elements with a groove or grooves on the face of same

along their upper edge to break capillary suction of water between elements.

A still further object is to provide elements which are economical to form, may be formed with practically no waste, are simple and economical to lay, and reduce to a minimum labor cost per unit area covered.

Further objects and advantages will appear as the description proceeds.

10 To the accomplishment of the foregoing and related ends, the invention, then, consists of the means hereinafter fully described and particularly pointed out in the claims, the annexed drawings and the following description setting forth 15 in detail certain means for carrying out the invention, such disclosed means illustrating, however, but several of various ways in which the principle of the invention may be used.

In said annexed drawings:

20 Figure 1 shows a typical blank from which both wide and narrow exposure elements may be cut.

Figure 2 is a face view of a narrow exposure element.

25 Figure 3 is a face view of a wide exposure element.

Figure 4 is a face view of a special form of narrow exposure element with a groove along its upper edge.

30 Figure 5 shows a two unit element of the narrow exposure type.

Figure 6 shows a special form of a single unit of wide exposure element.

Figure 7 shows another special form of a single unit of wide exposure element.

35 Figure 8 shows a special element adapted for two course exposure.

Figure 9 shows a modified form of the element shown in Figure 8.

40 Figure 10 is a section view along the line 10-10 of Figure 4.

Figure 11 shows a side and end view of a filler strip for use in connection with the element of Figures 8 and 9.

45 Figure 12 shows the mode of assembling the elements about a two-course height element.

Figure 13 shows the assembly of three courses of the elements.

50 Figure 14 is a face view of a conventional assembly of the elements as they appear when mounted on a suitable surface.

Figure 15 shows a two unit element of the wide exposure type.

55 Figure 16 shows a special form of two unit narrow exposure element.

Figure 17 shows a special form of a single unit of narrow exposure element.

The common practice in forming asbestos shingles is to first form a sheet and cut same to a 48" square size. This sheet in turn may be cut up into shingles or the like. For simplicity of understanding the present invention, it will be described in terms of using the 48" x 48" sheets of asbestos shingle stock. If this sheet is cut into quarters, then each quarter can be cut, as shown in Figure 1, to form two narrow exposure and two wide exposure elements, all of which will be 24" long. Instead of cutting the sheet into quarters, it may be cut full length, and thus produce eight 48" length elements, four of which are narrow exposure and four wide exposure. 60 The sheet may also be cut vertically 16" from either the right or left end, and thus produce four 32" length narrow exposure elements, four 32" length wide exposure elements, four 16" length narrow exposure elements, and four 16" 70 length wide exposure elements. From this, it is to be noted that the elements are multiples of 8" length units. This particular size has been merely chosen for simplicity of understanding the principles of the invention as set out herein, and under no consideration is to be construed as a limitation of the invention, since the elements may be of various sizes, so long as the principles set forth herein are complied with. The elements may also be cut with straight bottom edges, or 10 with uneven bottom edges which simulate hewed stone, either of which can be considered to be diagrammatically shown in the drawings.

15 Referring more particularly to Figure 1, the blank 1 may be cut to form a pair of narrow exposure elements 2 and a pair of wide exposure elements 3. The ends of the wide and narrow exposure elements may be started at any prescribed point. For instance, at the center of one of the tongues, the center of the hollow between a pair 20 of the tongues, or otherwise. However, in order to have all of the narrow exposure elements alike, and all of the wide exposure elements alike, the cutting should be such that the edge of the elements will start at approximately the center of 25 the inclined edge on the side of one of the tongues, as shown in Figure 1. After the cutting is completed and the elements separated, the narrow exposure element 2 and the wide exposure element 3 will have the general appearance as 30 shown in Figures 2 and 3 respectively. These elements are provided with nail holes 4 which may be formed simultaneously with the cutting of the elements, or separately afterwards. The elements may be used with straight-cut side edges 35 if desired. However, they may be provided with a relatively narrow notch 5 on one or both edges so as to simulate a mortar filled joint when laid in prescribed order. The notches are preferably of a height which will be substantially equal to 40 the exposure with which the element is to be laid. When the elements are butted together, the portion of the edge above notch 5 will act to close the opening between elements and hence avoid "wind tunnels" at the butted edge. 45

A convenient size for the elements wherein 8" length units or a multiple thereof are used, involves, in case of the 2 1/2" exposure element, tongues which are spaced at 8" centers and have a height of 4 3/4", the distance from the bottom 50 of the element to the bottom of the hollow between the tongues being 3". The width of the end of the tongues is preferably 2", and the width of the bottom of the hollow also 2". Where the element has an exposure of 5", the tongues are 55 preferably made 2 1/4" high, and the distance from the bottom of the element to the bottom of the hollow between tongues 5 1/2". The width of the end of the tongues and of the bottom of the hollows between the tongues is also preferably 2". 60 When these elements are laid up in alternating rows of wide exposure elements and then narrow exposure elements, et cetera, with joints over the center of tongues of the next lower course, such tongues will extend 1/4" above the upper edge of 65 the exposed face of the element next adjacent thereto. This is an ample underlap under normal conditions. The amount of exposure, however, may be decreased and the underlap correspondingly increased. The nail holes 4 are 70 preferably placed at a distance from the bottom of the element such that when the chosen exposure is attained and a vertical joint made over the center of a tongue of the next adjacent lower element, at least part of the holes will be over the 75

end of the tongue or tongues of the next lower course, and hence the overlap can be quickly determined by passing nails through the holes in such element and allowing it to lower until the 5 nails come in contact with the ends of the tongues of the next lower element before nailing. This procedure not only has the advantage of determining when the chosen overlap has been attained, but also it aids in speeding up the laying 10 of the elements.

One of the practical forms of construction for 15 these elements consists in using the same base material as is used in forming the conventional asbestos shingles. However, if desired, these 20 elements may be made of slate, asphalt shingle stock, metal coated with enamel, or the like. Another form of construction would be to mold the elements from a material such as commonly 25 known to the trade as a plastic. These, in general, are formed from material such as phenolic resins, which normally are supplemented with a filler material to reduce the cost. Where the 30 elements are molded, they can be provided, if desired, with a highly polished surface, may be 35 made relatively thin, and the tongues may be made narrower at their base, as shown in Figure 4. Where the element has a highly polished, or even a relatively smooth surface, there is a tendency for water to creep by capillary action 40 between adjacent courses. To overcome this, the upper face of the element 2a (Figures 4 and 10) may be provided with a groove 6. The use 45 of the groove 6, however, is not limited to highly polished elements, but is likewise adaptable to 50 any of the elements of the present invention.

By using the long tongues on the narrow exposure elements and the short tongues on the wide exposure elements, the tongues in each case will be sufficiently long to underlie and extend above the upper end of the exposed portion 40 of the vertical joint between elements in the same course. This permits continuous alternate placing of wide and narrow exposure elements, and also permits the continuous placing of one 45 or more courses of narrow exposure elements, one over the other without an opening direct to the surface under the joints, all of which combinations are shown assembled together with the two-course height elements of both 50 kinds, in Figure 14.

Stone buildings, such as those that are formed from hewed limestone blocks adapted to be laid in wide and narrow courses, normally have intermingled therewith for breaking the monotony 55 thereof, some substantially rectangular stones which are two courses high. The present invention has been devised so that two-course elements may also be utilized. Where a two-course element is to be placed with its bottom 60 in line with the bottom of a wide exposure course of elements, special joiner elements are necessary and these special elements may be of one or more unit lengths. At the left of the two-course element 7 (Figure 9) may be placed 65 joiner element 8 (Figure 6) which has had its upper right-hand corner cut back from the full size shown in dotted lines to the edge shown by the heavy line. The right-hand joiner element 9 (Figure 7) likewise has its upper left-hand corner cut away to the heavy line. The cutting away of the corners of joiner elements 8 and 9 makes room for ears 10 and 11 respectively of the two-course element 7. Suitable holes 12 and 13 are provided respectively in the 70 ears 10 and 11 for the nailing of the two-course

element 7 in place. In Figure 12 is shown an assembly wherein a two-course element 7 is placed between joiner elements 9 and 8a, the latter, for convenience of showing and breaking joints, being two units long instead of the single 5 unit shown in Figure 6. With the first joining course of wide exposure elements in place on opposite sides of two-course element 7, it is now ready for the placing thereon of a narrow exposure course. This requires special right and 10 left upper joiners for the two-course element 7. These special joiners may be formed, for instance, as is shown in Figure 5 by cutting a two unit length narrow exposure element in two along the dotted line 14 at the center of a hollow 15 between tongues, thus producing a left-hand upper joiner element 15 and a right-hand upper joiner element 16. The placing of these upper joiner elements 15 and 16 over the ears of the two-course element 7, as shown in Figure 12, is, 20 so far as that course is concerned, the same as taking a three unit length element and cutting the center tongue therefrom starting at the center of the hollows on each side of same, since the width of the base of the two-course element 25 7 is 8" and that is identical with the width of a single unit of the tongued elements. The next course, which would normally be of wide exposure, may then be laid in place across the top of the two-course element 7 and upper joiner 30 members 15 and 16 at their upper exposure line. However, if this were to be done, it would leave an 8" length opening across the top of the two-course element 7, such opening being of the same thickness as the upper joiner members 15 35 and 16. To avoid this condition, a strip 17 with nail holes 18 is nailed across the top of the two-course element 7, the lower edge of the strip 17 preferably being in line with the bottom edge of the course laid thereover. 40

Where the two-course element is to be started with its bottom in line with the bottom of a course of narrow exposure elements, then two-course element 19 is used. The assembly in this case is identical to that described in connection 45 with Figure 12 except that the two courses joined by the two-course element are laid in reverse order, i. e., the narrow exposure course is at the bottom, and the wide exposure course at the top. At the left of the two-course element 19 (Figure 50 8) is placed a narrow exposure left-hand joiner element 24 (Figure 16) which has its upper right-hand corner cut back to the edge shown by the heavy line. The narrow exposure right-hand joiner element 25 (Figure 17) likewise has its 55 upper left-hand corner cut away to the heavy line. The cutting away of the corners of joiner elements 24 and 25 makes room for ears 20 and 21 respectively of the two-course element 19. Suitable holes 22 and 23 are provided respectively 60 in the ears 20 and 21 for the nailing of the two-course element 19 in place. With the first joining course of narrow exposure elements in place on opposite sides of two-course element 19, it is now ready for the placing thereon of a wide 65 exposure course. This also requires special left and right upper joiners for the two-course element 19. These special joiners may be formed, for instance, as is shown in Figure 15, by cutting a two unit length wide exposure element in two 70 along the dotted line 26 at the center of a hollow between tongues, thus producing a left-hand upper joiner element 27 and a right-hand upper joiner element 28. These left and right hand upper joiner elements 27 and 28 are placed over left 75

and right hand joiner elements 24 and 25 respectively at the prescribed exposure distance above the bottom thereof in identical manner to the placing of elements 15 and 16 as shown in Figure 12. Strip 17 is then nailed across the top of the two-course element 18. The next higher course, which would normally be of narrow exposure, may then be laid in place across the top of upper left and right hand joiner elements 21 and 28 and over the upper end of two-course element 18 with strip 17 thereon, at the proper exposure distance above the bottom of left and right hand upper joiner elements 27 and 28. This completes the laying of a two-course element with its bottom in line with the bottom of a narrow exposure course. It is to be noted in connection with the two-course elements 1 and 18 that by cutting the ears as shown, no opening is presented at the lower edge of the ears where access may be had direct to the surface underneath the elements.

A further variation may be had by dropping strip 17 so that its lower edge is below the bottom of the next higher course laid over a two-course height element such as 1 or 18. This gives 25 the appearance of a thin stone between the top of element 1 or 18 and the next higher course. To accomplish this, strip 17, or its equivalent, may be nailed in place through holes 29 with the strip dropped down until the nails contact the top 30 of element 1 or 18. A typical installation of this nature is shown in Figure 14.

The present invention has been described in terms of combinations of two-course height elements 1 and 18 with narrow exposure elements 35 adapted for 2½" exposure and wide exposure elements adapted for 5" exposure, both the wide and narrow exposure elements being formed from an 8" length unit or a multiple of such units. When using elements of these sizes and 40 exposures, then the two-course elements may be considered as rectangular units with side ears. These rectangular units will be 8" wide and preferably 8½" high. The ears are preferably 1" wide, located along the side edges of the element, 45 and normally terminate at the upper edge thereof. These ears on two-course element 1 are approximately 2½" long on their outer edge and taper so as to be approximately 3½" long where the lower end of the ears joins the vertical sides 50 of the two-course element 1. The ears on two-course element 18 are also 1" wide and are approximately 5½" long on their outer edge and taper to approximately 6" long where the lower end of the ear joins the vertical sides of the two-course element 18. The above dimensions give a 55 1" underlap at the upper edge of the two-course element, as well as a 1" side lap at the ears. There is, however, no particular limitation to this particular amount of underlap and side lap, 60 and same may be varied so long as a satisfactory amount of undercoverage is retained. A typical installation of the two-course elements 1 and 18 is shown in Figure 14.

Other modes of applying the principle of my 65 invention may be employed instead of those explained, change being made as regards the mechanism herein disclosed, provided the means stated by any of the following claims or the equivalent of such stated means be employed.

70 I therefore particularly point out and distinctly claim as my invention:—

1. A surface covering comprising alternating rows of narrow exposure and wide exposure elements, said narrow exposure and wide exposure 75 elements both having tongues at regular inter-

vals along the upper edge thereof, said wide exposure element being higher from its base to the base of its tongues than is said narrow exposure element from its base to the base of its tongues. 5

2. A surface covering comprising alternating rows of narrow exposure and wide exposure elements, said narrow exposure and wide exposure elements both having tongues at regular intervals along the upper edge thereof, said tongues 10 on the narrow exposure elements being longer than those on the wide exposure elements.

3. A surface covering comprising alternating rows of narrow exposure and wide exposure elements, said narrow exposure and wide exposure 15 elements both having tongues at regular intervals along the upper edge thereof, each of said narrow exposure elements being shorter from its base to the base of its tongues than the length of its tongues, and each of said wide exposure elements being wider from its base to the base of its tongues. 20

4. A surface covering comprising alternating horizontal rows of narrow exposure and wide exposure elements, said narrow exposure and wide 25 exposure elements both having tongues at regular intervals along the upper edge thereof, said elements being cut to at least one unit length and at identical points on the ends thereof for matching and making complete tongues in manner 30 such that when laid in courses with the butted joints of the elements of one course over the center of the tongues of the next adjacent lower course and undercovered thereby to an extent greater than the exposure of said undercovered 35 course, the center of the tongues of each course will be shifted sidewise from course to course whereby the butted joints of adjacent courses will be staggered in manner preventing one falling over the other. 40

5. A surface covering comprising alternating rows of tongued narrow exposure and tongued wide exposure elements having interspersed 45 therein at intervals, two-course height elements.

6. A surface covering comprising alternating rows of tongued narrow exposure and tongued wide exposure elements, with two or more narrow exposure courses placed together at intervals. 50

7. A surface covering comprising alternating rows of tongued narrow exposure and tongued wide exposure elements, with two or more narrow exposure courses placed together at intervals, and interspersed at intervals in said alternating rows of narrow exposure and wide exposure elements, two-course height elements. 55

8. A surface covering comprising alternating rows of narrow exposure and wide exposure elements, said narrow exposure elements having spaced apart long tongue-like members projecting upward from their upper edge to form a complete underlap at the point of butted edge joints of the next higher course of covering elements, and said wide exposure elements having short tongue-like members projecting upward from their upper edge to form a complete underlap at 60 the point of butted edge joints of the next higher course of narrow exposure covering elements. 65

9. A surface covering comprising alternating rows of narrow exposure and wide exposure elements, said narrow exposure elements having 70 spaced apart long tongue-like members projecting upward from their upper edge to form a complete underlap at the point of butted edge joints of the next higher course of covering elements, said wide exposure elements having short tongue- 75

like members projecting upward from their upper edge to form a complete underlap at the point of butted edge joints of the next higher course of narrow exposure covering elements, and at least one groove adjacent the upper edge of the face of each of said narrow exposure and wide exposure elements and following the general contour thereof.

10. In a surface covering material adapted to be laid so as to simulate a stone wall, the combination of courses of narrow exposure and wide exposure elements, the narrow exposure element course having relatively long tongue-like members uniformly spaced along its upper edge, and
15. the wide exposure element course having relatively short tongue-like members uniformly spaced along its upper edge, said tongue-like members in either case being of a length such that when the elements are properly laid, the
20. tongues will underlie the joints of the next higher course of elements and extend above the upper exposure line thereof.

11. A surface covering element having a substantially rectangular base portion, inclined edge tongues projecting from one of the lengthwise edges of said base portion and spaced at regular intervals, said tongues having a wide base and a narrower flat point substantially centrally located thereabove, said surface covering element being cut to at least one unit length, the cutting at one end of the element starting approximately at the center of one of the inclined edges of a tongue so as to leave the major portion of the tongue on said base portion, and the cutting at the other end of the element being at the approximate center of the inclined edge of another tongue and parallel to the cut on the other end of the element, but leaving only a minor portion of said tongue on said base portion, said units in completed form being such that when laid in rows, end to end, and in identical order, the cut ends will match to form complete tongues.

45 12. In a surface covering element of the character described, the combination of a substantially rectangular base portion, tongues on the upper edge thereof at regular intervals, and at least one groove adjacent the upper edge of the face of said element and following the general contour thereof.

50 13. In a surface covering material adapted to
be laid so as to simulate a stone wall laid in al-
ternating wide and narrow exposure courses with
interspersed two-course exposure elements, the
combination which includes a substantially rec-
55 tangular element which is substantially higher
than the added exposure of the two courses in
which it is to be laid with its lower edge in line
with the lower edge of the bottom of said courses,
ears projecting from the sides of said substan-
60 tially rectangular element, the upper edge of said
ears being adjacent the upper edge of the ele-
ment, and means for anchoring said ears to a
suitable surface.

14. In a surface covering material adapted to be laid so as to simulate a stone wall laid in alternating wide and narrow exposure courses with interspersed two-course exposure elements, the combination which includes a substantially rectangular element which is substantially higher than the added exposure of the two courses in which it is to be laid with its lower edge in line with the lower edge of the bottom of said courses, ears projecting from the sides of said substantially rectangular element, the lower edge of said ears being cut so as to intermesh with the upper

adjacent corners of the lower of the two courses in which the substantially rectangular element is laid, and means for anchoring said ears to a suitable surface.

15. In a surface covering material adapted to be laid so as to simulate a stone wall laid in alternating wide and narrow exposure courses with interspersed elements for breaking the monotony thereof, the combination which includes alternating courses of narrow exposure elements and wide exposure elements, the narrow exposure element course having relatively long tongue-like members uniformly spaced along its upper edge, and the wide exposure element course having relatively short tongue-like members uniformly spaced along its upper edge, said tongue-like members in either case being of a length such that when the elements are properly laid, the tongues will underlie the joints of the next higher course of elements and extend above the upper exposure line thereof, a substantially rectangular element which is substantially higher than the added exposure of the two courses in which it is to be laid with its lower edge in line with the lower edge of the bottom of said courses, ears projecting from the sides of said substantially rectangular element, right and left joiner elements in said lower course, the upper adjacent corners of said joiner elements being cut away downward and toward the substantially rectangular element to be joined, the lowermost edge of said cut away corners terminating approximately at the upper exposure line of said elements, the ears on said rectangular element being cut at their under edge to intermesh with the cut away corners of the lower right and left joiner elements, right and left upper joiner elements having their inner ends laid so as to just cover the width of the ears of the rectangular element, a strip that is the thickness of the right and left upper joiner elements and of a length equal to the width of the base of said rectangular element, said strip being fastened between the right and left upper joiner elements at the top of said rectangular element with the base of the strip in line with the upper exposure line of the right and left upper joiner elements.

16. In a surface covering material adapted to be laid so as to simulate a stone wall laid in alternating wide and narrow exposure courses with interspersed elements for breaking the monotony thereof, the combination which includes alternating courses of narrow exposure elements and wide exposure elements, the narrow exposure element course having relatively long tongue-like members uniformly spaced along its upper edge, and the wide exposure element course having relatively short tongue-like members uniformly spaced along its upper edge, said tongue-like members in either case being of a length such that when the elements are properly laid, the tongues will underlie the joints of the next higher course of elements and extend above the upper exposure line thereof, a substantially rectangular element which is substantially higher than the added exposure of the two courses in which it is to be laid with its lower edge in line with the lower edge of the bottom of said courses, ears projecting from the sides of said substantially rectangular element, right and left joiner elements in said lower course, the upper adjacent corners of said joiner elements being cut away downward and toward the substantially rectangular element to be joined, the lowermost edge of said cut away corners terminating approximately at the upper

- exposure line of said elements, the ears on said rectangular element being cut at their under edge to intermesh with the cut away corners of the lower right and left joiner elements, right and left upper joiner elements formed with their left and right ends respectively terminating in a vertical line at the center of a hollow between tongues, said ends being laid so as to just cover the width of the ears of the rectangular element,
- 5 10 a strip that is the thickness of the right and left upper joiner elements and of a length equal to the width of the base of said rectangular element, said strip being fastened between the right and left upper joiner elements at the top of said rectangular elements with the base of the strip in line with the upper exposure line of the right and left upper joiner elements.
